UNITED STATES PATENT OFFICE.

SAMUEL AVERY, OF PHœNIX, NEW YORK.

DESIGN FOR TOP OF BURIAL-CASKET.

Specification forming part of Design No. 6,020, dated August 13, 1872.

Spécification for a new and original Design for Ornamental and Ornamented Top for Burial-Casket, invented by SAMUEL AVERY, of Phœnix, Oswego county, New York.

The nature of my design is fully represented in the accompanying illustration, to which reference is made.

The design is for the construction of a more beautiful and ornamental top for a burial-casket.

A represents the glass cover; B, the panel on the lower portion; c c c c c c, projections

on glass cover and panel. d d d d d are ornaments, made of wood or any other material. e e e show the form of each end of the glass cover and upper end of panel.

What I claim is—

The design for top of casket, as shown in the accompanying drawing.

SAMUEL AVERY.
